US00D371110S

United States Patent [19]

Harris et al.

[11] Patent Number: Des. 371,110

[45] Date of Patent: **Jun. 25, 1996

[54] POWER CONVERTER

[75] Inventors: Philip M. Harris, San Diego, Calif.; Paul A. Jeffries, Plano, Tex.

[73] Assignee: Natel Engineering Company, Inc., Simi Valley, Calif.

[**] Term: 14 Years

[21] Appl. No.: 34,905

[22] Filed: Feb. 15, 1995

[52] U.S. Cl. D13/110

[58] Field of Search D13/110; 363/15, 363/34, 143, 146; 336/107

[57] CLAIM

The ornamental design for "power converter", as shown and described.

DESCRIPTION

FIG. 1 is a perspective view of a power converter showing our new design;

FIG. 2 is an end elevational view thereof, the opposite end being the same except for the thickness of the outer pins;

FIG. 3 is a bottom plan view thereof;

FIG. 4 is a top plan view thereof;

FIG. 5 is a side elevational view thereof;

FIG. 6 is a side elevational view thereof, the opposite side shown in FIG. 5;

FIG. 7 is a perspective view of a second embodiment of a power converter showing our new design;

FIG. 8 is an end elevational view thereof, the opposite end being the same except for the thickness of the outer pins;

FIG. 9 is a bottom plan view thereof;

FIG. 10 is a top plan view thereof;

FIG. 11 is a side elevational view thereof; and,

FIG. 12 is a side elevational view thereof, the opposite side shown in FIG. 11.
